INVENTOR:

Charles P. Mosher
By Jacob Falbel
His ATTORNEY

UNITED STATES PATENT OFFICE.

CHARLES PHILO MOSHER, OF NEW YORK, N. Y., ASSIGNOR TO UNION TYPEWRITER COMPANY, OF ILION, NEW YORK, A CORPORATION OF NEW YORK.

TYPE-WRITING MACHINE.

981,214.

Specification of Letters Patent. Patented Jan. 10, 1911.

Application filed October 24, 1910. Serial No. 588,659.

To all whom it may concern:

Be it known that I, CHARLES P. MOSHER, citizen of the United States, and resident of the borough of Brooklyn, city of New York, 5 in the county of Kings and State of New York, have invented certain new and useful Improvements in Type-Writing Machines, of which the following is a specification.

My invention relates to typewriting machines and more particularly to carriage supporting means, and the main object of said invention is to provide simple and efficient means of the character specified by which but little resistance is offered to the 15 travel of the carriage and by which the carriage will be firmly guided in its travel.

To the above and other ends my invention consists in the features of construction, arrangements of parts and combinations of devices to be hereinafter described and particularly pointed out in the appended claims.

In the accompanying drawings wherein like reference characters indicate corresponding parts in the various views, Figure 25 1 is a fragmentary vertical sectional view showing the upper portion of a typewriting machine embodying my invention. Fig. 2 is a vertical transverse sectional view of the same taken on the line $\alpha-\alpha$ of Fig. 1 and 30 looking in the direction of the arrow at said line. Fig. 3 is a transverse sectional view taken centrally through one of the pinions, to be hereinafter more fully described.

The top plate 1 of the machine is supported 35 on corner posts 2, and has upwardly and forwardly extending lugs or supports 3 thereon. A guide rod 4 is detachably secured to the lugs 3 by screws 5. The guide rod 4 has inclined tracks or flat bearing 40 faces 6 formed on opposite sides of the top thereof. These tracks 6 are preferably formed by grooving the guide rod longitudinally to form flat faces which are inclined at an angle to each other as indicated 45 in Fig. 1. The lower side of the rod has a groove 7 therein which extends longitudinally of the rod throughout, or substantially throughout, the length thereof. A rack 8 is firmly seated in said groove; the teeth of 50 the rack extending beyond the periphery of the guide rod at the lower side of the latter. The guide rod on opposite sides of the rack 8 is formed with flat faces 9 which constitute tracks against which peripheral bearings 10 55 on pinions 11 are adapted to bear for pur-

poses which will hereinafter more clearly appear.

The carriage proper may be of any suitable construction, but as shown in the present instance comprises end bars 12 having bearing openings for a shaft 13, on which a cylindrical platen 14 is mounted. The end bars 12 of the carriage are united by a forward cross bar 15, provided with an anti-friction roller 16 received between fixed 60 guide rails 17 and 18 secured to the top plate of the machine. The end bars 12 of the carriage are connected at the rear ends thereof by a bearing member, designated as a whole by the reference numeral 19. This 65 bearing member is in the nature of a sleeve which surrounds the guide rod 4, and is provided at the rear side thereof with longitudinally extending cut-outs or slots 20. These slots extend inwardly in opposite 70 directions from the ends of the bearing member and each slot terminates at 21 before the middle of the bearing member is reached, so as to provide a central connecting web 22. Thus a connection is formed between the upper and lower portions of the bearing member at the rear as well as at the front side thereof. By arranging the slots 20 in the manner shown, they are adapted to receive the forwardly extending portions of the 75 supports 3, as indicated in Fig. 2, and to afford a free movement of the ends of the bearing member past said supports in the travel of the carriage from side to side of the machine. The bearing member 19 is 80 provided with inclined tracks or bearing faces 23 on opposite sides thereof, for co-operation with cylindrical anti-friction bearing rollers 24, which have their axes inclined 85 in opposite directions to correspond to the 90 inclination of the associated bearing faces 23 and 6 on the bearing member and guide rod respectively.

A roller separator indicated as a whole 95 by the reference numeral 25, is in the nature 100 of a sleeve which surrounds the guide rod 4 and is itself surrounded by the bearing member 19. Rectangular openings 26 are formed near each end of the sleeve-like separator for the reception of the anti-friction 105 rollers 24. It will therefore be understood that the anti-friction rollers are maintained properly positioned and separated by the separator 25 in the travel of the carriage 110 from side to side of the machine.

In order to always maintain a definite relation between the roller separator and the carriage, and consequently between the anti-friction rollers and the carriage, I have 5 provided means which will now be described.

Depending ears 27 are formed on the separator near each end thereof. A pivot pin 28 extends through openings in each set of 10 the ears 27 and constitutes a pivot for a pinion 11 hereinbefore referred to. This pinion is preferably formed, as indicated in Fig. 3, of a central disk 29 provided with peripheral teeth 30. Disks 31 are arranged 15 on opposite sides of the disk 29 and are riveted thereto by rivets 32, so as to unite the three disks to constitute a single combination pinion and bearing roller. The disks 31 are provided with peripheral bearings 10, as hereinbefore pointed out. These bearings 20 are adapted to coact with the tracks 9 on the guide rod 4, whereas the teeth of the pinion mesh with the rack 8 secured to the guide rod. A plate-like member or support 33 extends longitudinally of the bearing member beneath the same and throughout, or substantially throughout, the length 25 of said bearing member. The platelike support 33 is provided near each end thereof with screws 34 and 35 on opposite sides of 30 the center of said plate. The screws 34 are received in tapped openings in the bearing plate and bear at their upper ends against inwardly directed flanges 36 on the bearing member. On the other hand, the screws 35 extend freely through openings in the plate 33, on opposite sides of the longitudinal center thereof, and are received in 35 tapped openings in the inwardly extending flanges 36 on the bearing member. By this 40 construction each end of the bearing plate 33 is provided with independent adjusting means by which it may be raised or lowered and fixedly maintained in its adjusted position 45 on the bearing member of the carriage. Thus, by loosening the screws 34 and tightening the screws 35 the bearing plate 33 will be elevated or adjusted toward the bearing member on the carriage, whereas 50 when the screws 35 are loosened and the screws 34 tightened the bearing plate 33 will be lowered. The bearing plate 33 has a central longitudinally extending groove 37 therein, which preferably extends 55 throughout the length of the bearing plate. This longitudinally extending groove, or pocket, formed in the bearing plate is adapted to receive a rack 38 which cooperates 60 with the pinions 11. Near each end of the bearing plate 33 is a tapped opening in the bottom thereof to receive a screw 39 which extends through the tapped opening, and bears at its upper end against the bottom of 65 the rack 38 to effect a vertical adjustment of said rack. It will therefore be understood

that the screws 39 constitute individual adjusting means at opposite ends of the rack 38, whereby a relative adjustment between the racks 38 and 8 may be effected. Longitudinally extending tracks 40 are formed 70 on the bearing plate 33 on opposite sides of the rack 38. These longitudinally extending tracks or bearings 40 preferably extend throughout, or substantially throughout, the length of the bearing plate 33 and are 75 adapted to coöperate with the peripheral bearings 10 on the pinions 11. The peripheral bearings 10 will therefore be engaged on opposite sides by the tracks 9 of the guide rod and the tracks 40 of the bearing member 80 on the carriage. The roller separator 25 will thus be supported by the roller bearings 10 between said tracks 9 and 40, to maintain the separator out of contact with the guide rod 4, and to maintain it in 85 proper position out of contact with the bearing member 19 on the carriage. At the same time the peripheral bearings 10 prevent an upward displacement of the bearing member 19 relatively to the fixed guide rod 4. 90 The adjusting screws 34, 35 and 39 constitute means by which a nice relative adjustment between the parts may be effected; to compensate for wear; to maintain the parts in the proper relative positions; and to take 95 up any lost motion, so that the carriage may be firmly guided in its movement from side to side of the machine. Any tendency of fore and aft or downward displacement is overcome or resisted by the anti-friction 100 rollers 24, whereas the upward thrust of the bearing member 19 is resisted by the peripheral bearing members 10.

It will be observed that the pitch line of each of the pinions 11 is about coincident 105 with the companion peripheral bearings 10 so that the surface speed of the pinion and bearing members is the same.

It will be understood that the travel of the roller separator and each of the anti-friction rollers 24 is equal to one-half the extent of travel of the carriage, and that this relation is constantly maintained by the engagement of the pinions with the oppositely disposed racks on the fixed guide rod 110 and on the bearing member 19, which engage the pinions on opposite sides. The relation of the parts is such that when the carriage is centrally maintained on the frame of the machine, the anti-friction rollers and 115 the separator 25 will likewise be centrally positioned with reference to the frame of the machine and the carriage. When the carriage travels in either direction the anti-friction rollers and separator will travel in 120 the same direction one-half the distance traveled by the carriage, as indicated in Fig. 2.

Various changes may be made without departing from the spirit and scope of my invention.

What I claim as new and desire to secure by Letters Patent, is:—

1. In a typewriting machine, the combination of a carriage, a guide rod therefor, anti-friction rollers interposed between the carriage and said guide rod, and a roller separator which coöperates with said rollers, said separator being in the nature of a sleeve which surrounds said guide rod.
2. In a typewriting machine, the combination of a carriage, a guide rod therefor, anti-friction rollers interposed between the carriage and said guide rod, a roller separator which coöperates with said rollers, said separator being in the nature of a sleeve which surrounds said guide rod, a pinion carried by said separator, a rack carried by said carriage, and a second rack carried by said guide rod, both of said racks meshing with said pinion.
3. In a typewriting machine, the combination of a carriage, a guide rod therefor, anti-friction rollers interposed between the carriage and said guide rod, a roller separator which coöperates with said rollers, said separator being in the nature of a sleeve which surrounds said guide rod, a pinion carried by said separator, a rack carried by said carriage, a second rack carried by said guide rod, both of said racks meshing with said pinion, and means for effecting a relative adjustment between said racks.
4. In a typewriting machine, the combination of a carriage including a bearing member in the nature of a sleeve, a guide rod which is surrounded by said sleeve, anti-friction rollers between said guide rod and bearing member, and a separator which surrounds said guide rod and which is surrounded by said bearing member and coöperates with said anti-friction rollers.
5. In a typewriting machine, the combination of a carriage including a bearing member in the nature of a sleeve, a guide rod which is surrounded by said sleeve, anti-friction rollers between said guide rod and bearing member, a separator which surrounds said guide rod and which is surrounded by said bearing member and coöperates with said anti-friction rollers, a pinion carried by said separator, a rack carried by said guide rod, and a second rack carried by said bearing member, both of said racks coöperating with said pinion on opposite sides thereof.
6. In a typewriting machine, the combination of a carriage including a bearing member in the nature of a sleeve, a guide rod which is surrounded by said sleeve, anti-friction rollers between said guide rod and bearing member, a separator which surrounds said guide rod and which is surrounded by said bearing member and coöperates with said anti-friction rollers, a pinion carried by said separator, a rack car-
- ried by said guide rod, a second rack carried by said bearing member, both of said racks coöperating with said pinion on opposite sides thereof, and means for effecting a relative adjustment between said racks.
7. In a typewriting machine, the combination of a carriage having a bearing member, a guide rod which is surrounded by said bearing member, cylindrical rollers that have inclined axes and which are interposed between the bearing member and said guide rod and bear against the guide rod on opposite sides thereof, and a separator for said rollers, said separator being in the nature of a sleeve which surrounds said guide rod and which is interposed between the rod and said bearing member.
8. In a typewriting machine, the combination of a carriage having a bearing member, a guide rod which is surrounded by said bearing member, cylindrical rollers that have inclined axes and which are interposed between the bearing member and said guide rod and bear against the guide rod on opposite sides thereof, a separator for said rollers, said separator being in the nature of a sleeve which surrounds said guide rod and which is interposed between the rod and said bearing member, a pinion carried by said separator, a rack carried by said bearing member, and a second rack carried by the guide rod, said racks coöperating with the pinion on opposite sides thereof.
9. In a typewriting machine, the combination of a carriage having a bearing member, a guide rod which is surrounded by said bearing member, cylindrical rollers that have inclined axes and which are interposed between the bearing member and said guide rod and bear against the guide rod on opposite sides thereof, a separator for said rollers, said separator being in the nature of a sleeve which surrounds said guide rod and which is interposed between the rod and said bearing member, a pinion carried by said separator, a rack carried by said bearing member, a second rack carried by the guide rod, said racks coöperating with the pinion on opposite sides thereof, and means for effecting a relative adjustment between said racks.
10. In a typewriting machine, the combination of a guide rod supported on the top plate of the machine, a carriage having a bearing sleeve which surrounds said guide rod and which is provided with cut-outs or slots to receive the supports for said guide rod and afford an unobstructed movement of the ends of the bearing sleeve past said supports, and anti-friction rollers between said bearing sleeve and guide rod.
11. In a typewriting machine, the combination of a guide rod supported on the top plate of the machine, a carriage having a bearing sleeve which surrounds said guide rod and which is provided with cut-outs or slots to receive the supports for said guide rod and afford an unobstructed movement of the ends of the bearing sleeve past said supports, and anti-friction rollers between said bearing sleeve and guide rod.

rod and which is provided with cut-outs or slots to receive the supports for said guide rod and afford an unobstructed movement of the ends of the bearing sleeve past said supports, anti-friction rollers between said bearing sleeve and guide rod and bearing against the top of the rod on opposite sides thereof, a separator in the nature of a sleeve which surrounds said rod and which is interposed between the rod and said bearing sleeve, and means for causing the separator to travel one half the distance of the carriage.

12. In a typewriting machine, the combination of a guide rod supported on the top plate of the machine, a carriage having a bearing sleeve which surrounds said guide rod and which is provided with cut-outs or slots to receive the supports for said guide rod and afford an unobstructed movement of the ends of the bearing sleeve past said supports, anti-friction rollers between said bearing sleeve and guide rod and bearing against the top of the rod on opposite sides thereof, a separator in the nature of a sleeve which surrounds said rod and which is interposed between the rod and said bearing sleeve, a pinion carried by said separator beneath the guide rod, a rack carried by the bearing sleeve, said racks coöperating with said pinion on opposite sides thereof.

13. In a typewriting machine, the combination of a guide rod supported on the top plate of the machine, a carriage having a bearing sleeve which surrounds said guide rod and which is provided with cut-outs or slots to receive the supports for said guide rod and afford an unobstructed movement of the ends of the bearing sleeve past said supports, anti-friction rollers between said bearing sleeve and guide rod and bearing against the top of the rod on opposite sides thereof, a separator in the nature of a sleeve which surrounds said rod and which is interposed between the rod and said bearing sleeve, a pinion carried by said separator beneath the guide rod, a rack carried by the

guide rod, a second rack carried by said bearing sleeve, said racks coöperating with 50 said pinion on opposite sides thereof, and means for effecting a relative adjustment between said racks.

14. In a typewriting machine, the combination of a carriage having a bearing member, a guide rod, anti-friction rollers between said bearing member and guide rod, a separator for said rollers, said separator being in the nature of a sleeve which surrounds said guide rod, a pinion carried by said 60 separator, said pinion having peripheral bearing portions, tracks on the bearing member and rod with which the peripheral bearings on the pinion coöperate, and racks on the bearing member and rod with which 65 the teeth of the pinion coöperate.

15. In a typewriting machine, the combination of a carriage having a bearing member, a guide rod, anti-friction rollers interposed between said bearing member and 70 guide rod, a separator in the nature of a sleeve which surrounds said guide rod and coöperates with said anti-friction rollers, and independent supporting rollers carried by said separator for supporting the 75 separator in place.

16. In a typewriting machine, the combination of a carriage having a bearing member, a guide rod, anti-friction rollers interposed between said bearing member and 80 guide rod, a separator in the nature of a sleeve which surrounds said guide rod and coöperates with said anti-friction rollers, independent supporting rollers carried by said separator for supporting the separator 85 in place, a support for said independent supporting rollers, and means for effecting an adjustment of said support.

Signed at the borough of Manhattan, city of New York, in the county of New York, 90 and State of New York, this 21st day of October A. D. 1910.

CHARLES PHILO MOSHER.
